United States Patent

Des. 235,199
Patented May 27, 1975

235,199

PIROGUE

Sam E. Schneider, Jr., 124 Ardmore,
Shreveport, La. 71105

Filed May 22, 1973, Ser. No. 362,787

Term of patent 14 years

Int. Cl. D12—06

U.S. Cl. D12—63

The single figure in the drawing is a perspective view of a pirogue showing my new design.

I claim:

The ornamental design for a pirogue, substantially as shown.
